PORTABLE COVER FOR DISPLAYING AND PROTECTING MERCHANDISE

Robert R. Nathans, 19464 Manor, Detroit, Mich.

Filed June 13, 1963, Ser. No. 75,339

Term of patent 3½ years

(Cl. D80—11)

The counter edge engaging arms are broken away in FIGURES 2 and 5 for convenience of illustration.

I claim:

The ornamental design for a portable cover by displaying and protecting merchandise, as shown and described.
